LOOSE LEAF BINDER

Adolph G. Lotter, Milwaukee, Wis., assignor to
 Stationers Loose Leaf Company, Milwaukee,
 Wis., a corporation of Wisconsin

Application January 12, 1933, Serial No. 651,257

6 Claims. (Cl. 129—9)

This invention relates to certain new and useful improvements in loose leaf binders, and refers more particularly to the provision of key controlled means for locking the binder closed, as 5 in Letters Patent No. 1,798,478, issued to Adolph G. Lotter, March 31, 1931.

It is a general object of this invention to provide an improved key controlled locking mechanism for the purpose described in which the locking 10 device is attached directly to the binder to preclude the possibility of its being lost.

Another object of this invention is to provide a small, compact locking mechanism of simple inexpensive construction mounted on the binder 15 in such a manner as not to interfere with the normal use of the binder.

And a further object of this invention is to provide a locking mechanism carried by a stationary part of the binder and having a locking 20 member engageable with the locking bar which serves to secure the separable sections together to prevent unauthorized actuation of the locking bar.

With the above and other objects in view which 25 will appear as the description proceeds, my invention resides in the novel construction, combination and arrangement of parts substantially as hereinafter described and more particularly defined by the appended claims, it being understood that such changes in the precise embodiment of the hereindisclosed invention may be made as 30 come within the scope of the claims.

In the accompanying drawing, I have illustrated one complete example of the physical embodiment of my invention constructed according 35 to the best mode I have so far devised for the practical application of the principles thereof, and in which:

Figure 1 is a top plan view of a visible record 40 loose leaf binder embodying this invention, parts thereof being broken away and in section;

Figure 2 is a section view taken through Fig. 1, on the plane of the line 2—2; but showing only the top portion of the binder head; and

Figure 3 is a perspective view of the locking 45 mechanism and the adjacent end of the locking bar.

Referring now more particularly to the accompanying drawing in which like numerals indicate 50 like parts throughout the several views, the numeral 4 designates generally the back of a loose leaf binder which may be of the visible record type illustrated in Letters Patent No. 1,727,348, issued September 10, 1929.

The back 4 comprises a stationary element 5, the side edges of which have hinge elements 6 attached thereto for hingedly connecting the covers (not shown) to the back. At its opposite ends, the stationary element 5 has overlying flanges 7 55 and 8, which serve to hold a pair of transversely

separable sections 9 and 10 on the stationary element. The sections 9 and 10 carry series of impaling prongs 11 and 12, respectively, which, when the binder is closed, normally have their ends engaged to form binder rings.

Under separation of the sections 9 and 10, the 65 series of prongs open and permit the insertion or removal of record leaves. Separation of the sections 9 and 10 is facilitated by handles 13 and 14 attached to the ends of the sections adjacent 70 the overlying flange 8.

When the separable sections are in abutting relationship, as illustrated in Fig. 1, and the binder 75 is said to be closed, the sections may be locked against separation by a longitudinally shiftable locking bar 15. This bar 15 extends throughout the length of the binder head and is positioned over the meeting edges of the separable sections. It is longitudinally slidably mounted by means of 80 posts 16 and 17 fixed to the stationary element 5 of the back adjacent the opposite end portions of the bar. A third post, not shown, is also preferably provided at the central part of the bar.

The posts 16 and 17 project through elongated 85 slots 18 and 19, respectively, in the bar and have enlarged heads overlying the upper face of the bar to retain the same assembled with the posts.

Adjacent the elongated slots 18 and 19 the bar 90 has interlocking connections with the separable sections indicated generally by the numeral 20. These interlocking connections comprise lugs 21 struck upwardly from the separable sections to project across the plane of the longitudinally shiftable bar. Adjacent these lugs the bar is provided with offset or raised portions 22 of sufficient height to permit the lugs 21 to pass therebeneath when the bar is moved to a position aligning the raised portions 22 with the lugs. Apertures 23 are cut into the bar at one end of 95 each raised portion 22, which apertures have narrow portions 24 formed in that part of the bar 100 engaging the separable sections, and wider portions 25 formed in the raised parts 22. Inclined sides 26 connect the wide and narrow portions of the apertures so that when the bar is shifted in a direction to move the narrow portions 24 into alignment with the lugs 21, the lugs will be drawn together and securely held against separation to thereby secure the separable sections together.

The slot 19 in which the post 17 is received has 110 a pair of tangs 27 struck outwardly from its sides to abut the head of post 17 when the bar is shifted to its locking position, and a compression spring beneath the bar urges the bar upwardly against the head of the post and maintains the locking connection between the tangs 27 and the head of the post. Consequently to shift the bar and free the sections for separation, it is necessary to depress the adjacent portion of the bar 115 and disengage the tangs 27 from the head of the 120

post 17. This structure is similar to that shown in Patent No. 1,727,348, issued to Adolph G. Lotter, September 10, 1929.

This inter-engagement of the tangs 27 and head 5 of the post is sufficient to prevent accidental shifting of the locking bar, but does not prevent unauthorized shifting thereof. For this purpose, the novel locking mechanism of this invention is provided.

10 The locking mechanism is indicated generally by the numeral 28 and is mounted at the end of the binder back having the overlying flange 7. It comprises a tumbler lock 29 having a cylinder 30 rotatably mounted in a casing 31. The lock cylinder 30 is provided with the usual spring-pressed tumblers 32 engageable in locking grooves formed in the casing 31 and retractable to free the cylinder for rotation by the insertion of a proper key 33.

20 The casing 31 has attaching ears 34 formed on its offset sides which are riveted to the flange 7 as at 35. The lock cylinder is held assembled with the casing 31 by the engagement of an enlarged flange 36 on its inner end, in a groove 37 formed 25 in a projection 38 on the adjacent end of the casing. The flange 36 is cut away at 39 to permit the projection 38 to be passed therethrough so that the lock cylinder may be assembled with the casing. After assembly, a stop pin 40 is driven into the end of the lock cylinder so as to engage the projection 38 and preclude realignment of the opening 39 with the projection. The pin 40 thus serves to define one of the limits of rotation of the lock cylinder.

35 The other limit of rotation is defined by the engagement of a locking bolt 41 projecting radially from the inner end of the lock cylinder with the projection 38 as best illustrated in Fig. 2. One side of the locking bolt also defines one 40 end of the outlet opening 39.

45 The locking bolt 41 is adapted to swing down into an aperture 42 cut into the adjacent end portion of the locking bar 15. The aperture 42 may be in communication with the slot 18, although this is not necessary.

To enable alignment of the aperture 42 with the locking bolt 41 and to obviate increasing the size of the binder back, the flange 7 is preferably cut away, as at 43, to accommodate the adjacent end 50 portion of the bar 15.

55 The operation of the locking mechanism is extremely simple, for to lock the binder it is only necessary to shift the bar 15 to its operative locking position and then turn the lock to engage the bolt 41 in the aperture 42.

From the foregoing description taken in connection with the accompanying drawing, it will be readily apparent to those skilled in the art to which an invention of the character described 60 appertains, that this invention affords a novel and simple locking mechanism for loose leaf binders and that by reason of its simplicity and small size, it does not interfere with the normal use of the binder.

65 What I claim as my invention is:

1. The combination with a loose leaf binder comprising prong carrying sections transversely separable on substantially a common plane and a movable member for securing the prong carrying sections against separation, said movable member being longitudinally movable into and out of engagement with abutments carried by both of said prong carrying sections, of a key op-

erable locking device, means to permanently mount the locking device adjacent one end of the movable member, and a locking bolt actuated by said locking device and engageable with the movable member to releasably secure the same against longitudinal movement from a position actively engaging the abutments of both sections.

2. The combination with a loose leaf binder having prong carrying sections mounted on a stationary element for flatwise motion toward and from each other, of a locking mechanism to secure said sections against movement, comprising a member having an interlocking connection with said sections which connection is releasable upon longitudinal movement of said member in one direction, a key controlled locking member permanently mounted on said stationary element, and a cooperating interlocking connection between said locking member and the movable member to secure said movable member against longitudinal movement in said direction.

3. In combination with a loose leaf binder of the type having separable prong carrying sections mounted on a supporting back and a longitudinally shiftable locking bar operable to secure the prong carrying sections against separation, of a locking device including a rotatable key controlled lock cylinder, a mounting barrel for the cylinder permanently fixed to part of the supporting back, and a locking bolt movable with the cylinder into 105 and out of locking engagement with said longitudinally shiftable bar to secure the bar against longitudinal movement.

4. In a loose leaf binder including relatively movable prong carrying sections and a longitudinally shiftable locking bar operable to secure the prong carrying sections against relative movement, of locking means to secure the longitudinally shiftable bar against movement and lock the sections closed, comprising, a lock cylinder having key operable tumblers, a casing to mount the lock cylinder adjacent one end of said longitudinally shiftable bar, and a locking bolt on the lock cylinder engageable in an aperture formed in the locking bar to secure the same 110 against shifting.

5. In a loose leaf binder having transversely separable prong carrying sections mounted on a stationary element and having a longitudinally shiftable locking bar operable to secure the prong carrying sections against separation, of locking means to lock the bar against shifting, comprising a lock cylinder having key operable tumblers, a casing for the lock cylinder permanently attached to said stationary element adjacent one 125 end of the locking bar, and a locking bolt on said cylinder engageable with the locking bar to secure the same against longitudinal shifting.

6. In a loose leaf binder having transversely separable prong carrying sections movably mounted on a stationary element which stationary element is provided with a flange overlying the prong carrying sections, a longitudinally shiftable locking bar operable to secure the prong carrying sections against separation and having 135 one end disposed near the overlying flange, a tubular casing attached to said overlying flange, a lock cylinder having key operable tumblers mounted in said casing and a locking bolt on said cylinder engageable with the longitudinally shiftable locking bar to secure the same against longitudinal shifting.

ADOLPH G. LOTTER.
